UNITED STATES PATENT OFFICE.

AUSTIN KING AITKIN, OF TRENTON, NEW JERSEY, ASSIGNOR TO JAMES J. DALE,
TRUSTEE, OF TRENTON, NEW JERSEY.

DESIGN FOR AN ARTICLE OF MANUFACTURE.

47,680.

Specification for Design. Patented Aug. 10, 1915.

Application filed May 25, 1915. Serial No. 30,468. Term of patent 14 years.

To all whom it may concern:

Be it known that I, AUSTIN KING AITKIN, a citizen of the United States, and a resident of the city of Trenton, in the county of Mercer and State of New Jersey, have invented a new, original, and ornamental Design for an Article of Manufacture, of which the following is a specification, reference being had to the accompanying drawing forming part thereof, in which—

The figure of the drawing is a view of my design.

The part marked A shows in broken lines part of an article of manufacture to which my design may be applied. The part marked B represents the design itself.

Copies of this patent may be obtained for five cents each, by addressing the "Commissioner of Patents, Washington, D. C."

My design may be stamped, printed, imprinted, embossed, or worked on or in, or cut upon or in, any suitable paper, cloth, or any other fabric, or upon any metal or any other suitable material, and may be produced on or in, or attached to any desired article of manufacture.

I claim:

The ornamental design for an article of manufacture as shown and described.

AUSTIN KING AITKIN.
